F. A. SULLIVAN

REFLECTOR

Filed March 10, 1923

REFLECTOR
FLORENCE A. SULLIVAN.

By Arthur E. Wallace Atty.

UNITED STATES PATENT OFFICE.

FLORANCE A. SULLIVAN, OF PORTLAND, OREGON.

REFLECTOR.

Application filed March 10, 1923. Serial No. 624,068.

To all whom it may concern:

Be it known that I, FLORANCE A. SULLIVAN, a citizen of the United States, residing at Portland, in the county of Multnomah 5 and State of Oregon, have invented a new and useful Reflector, of which the following is a specification.

The present invention relates to reflectors, and has particularly to do with a type of 10 reflector adapted for use with automobile headlights and with portable lanterns.

The primary object of the invention is to provide a reflector producing an increased volume of what may be termed "flood light"; 15 and secondarily, to combine in a single reflector means for obtaining a concentrated or beam light in connection with a large volume of surrounding flood light.

These, and such other objects as may 20 hereinafter appear, are obtained by the novel construction, combination, and arrangement of the parts of my device.

Reference will now be had to the single 25 sheet of drawing accompanying this specification and made a part thereof, and in which:—

Fig. 1 is a vertical section of one form of my reflector and a typical railroad lantern mounting therefor;

30 Fig. 2 is a front view of the reflector; and

Figs. 3 and 4 are modified forms of the device adapting it for use upon automobile headlights.

35 Like reference characters are used to designate similar parts in the specification which follows and in the drawing.

Reference will be first had to Figs. 1 and 2. Ordinal 10 represents the body or battery housing of a portable railroad lantern 40 having at its bottom a plurality of legs 11, held in separated position by a ring-like member 12 adapted to be secured to legs 11 by soldering or brazing as is common in the art. Legs 11 are similarly secured to the body 10.

Ordinal 13 is used to indicate the reflector. This reflector comprises a central concave section 14 forming the internal reflecting surface, an annular external reflecting surface 15 contiguous to the concave section, and a rolled rim 16 about the external reflecting surface.

55 Protruding from the center of concave portion 14 is a lamp or light socket 17 into which an electric bulb or light 18 may be

screwed. Connection with the source of current may be had in any approved manner.

Reflector 13 may be permanently affixed 60 to body 10 or secured thereto for ready dissociation therefrom by enveloping flanges 13^a or by clips engaging rolled rim 16.

It is at once apparent that the light source is disposed in front of and on the 65 axis of the reflector 13. The socket 17 projects sufficiently far that the center of light in bulb 18 is positioned at a point forward of the intersection of imaginary lines as extensions to the surfaces 15 towards the 70 axis of the reflector. Concave portion 14 is quite shallow, so shallow that the rays of light emanating from the bulb 18 may be cast freely in all lateral directions.

Reflector 13 may be spun or stamped, and 75 nickelized, silvered, or polished as an aid to reflection.

The structure of the reflector 13 having been stated briefly, its effect when the bulb 18 is lighted will now be described.

80 Outwardly projected rays emanating from the bulb 18 will not be reflected but will continue in the direction of emanation. Rays of light striking the concave portion are concentrated, and projected forwardly in a beam of parallel rays or as a "spot" light. The reflector therefore has a two-fold utility—the production of a 85 luminous flood light spreading over a large sphere or field, and the production of a beam of light of parallel rays for the 90 intense illumination of a small field.

In automobile headlights, it is usual to provide a barrel or cylinder about the source of light and to use a lens at the outer end of such cylinder. Where reflector 13 is so employed upon an automobile headlight, or otherwise, wide diffusion of light occurs in conjunction with the formation of a "spot" light. This is particularly noticeable because the rays of light striking the surface 15 will be broken up and spread over a wide surface while a direct illumination by concentrated rays from the concave portion 14 will also be had.

100 The reflector disclosed in Fig. 3 is substantially identical with that disclosed in Figs. 1 and 2 except that instead of a rolled rim 16 a forwardly projecting flange is provided to fit within the barrel or body 105 of an automobile headlight. In this figure, the reflector is designated by the ordinal

33, the concave portion 34, the oblique annular reflecting surface 35, the flange 36, the socket 37, and the light bulb 38.

In Fig. 4, another modified form of the device is shown, the purpose thereof being to obtain the maximum distribution or diffusion of light rays. Such reflector, designated 43, comprises an oblique annular reflecting surface 45 disposed to disperse all rays of light striking it. An annular flange 46 identical with that shown in Fig. 3 is disclosed. There is in such construction no concentration of light rays into beams.

In the reflector shown in Fig. 3, the concave portion 34 will produce the "spot" effect hereinbefore described. The concentrated beams or plurality of light rays pass directly out of the lantern body through the lens ordinarily used in conjunction therewith.

In Fig. 4, the concave portion or pocket is missing. But the effect of the annular reflecting surface 45 is identical with that of the same surface, designated 15 in Fig. 1 and 35 in Fig. 3.

Rays of light emanating from bulb 18 and forwardly thereof will pass directly through the lens employed in conjunction with the interior. Rays of light directly striking the headlight 12 or the flanges 36 and 46 forward of the center of light will also pass through the headlight lens at a wide angle to add volume to the flood light by unreflected rays. Rays of light striking the interior of flanges 36 and 46 rearwardly of the center of light will be reflected rearwardly against the inclined surface 35 or 45 from which surfaces they will be re-

flected forwardly through the lens to augment the diffused flood light heretofore referred to.

As the inclined surfaces 35 and 45 are disposed rearwardly of the center of the source of light in the light bulb and the slightly oblique angle thereof is such that such surfaces receive the direct rays of light from the center thereof, additional rays are reflected against flanges 36 and 46 and the surrounding headlight body and by these outwardly through the lens to be diffused over a wide sphere. The surface indicated constitutes the principal origin of the soft or diffused light emanating from a headlight of this character and construction.

It is to be expressly understood that I do not limit myself to the specific forms of the invention shown herein nor to the proportions disclosed, but set forth what I believe to be new in the claim hereto appended.

I claim:

A reflector in combination with a centrally disposed point source of light, and comprising a concave section immediately adjacent said light source and an annular truncated cone plane surface of less width than the diameter of said concave section about said concave section and extending to the margin of said reflector, the outer edge of said plane surface and the bottom of said concave section being in the same plane, said source of light being at a point beyond the intersection of imaginary lines drawn as extensions to the surface of said truncated cone portion.

FLORANCE A. SULLIVAN.
